MOLDED PANEL OR SIMILAR ARTICLE

James M. Long, Granville, Ohio, assignor to Owens-Corning Fiberglas Corporation

Filed Apr. 17, 1972, Ser. No. 245,018

Term of patent 14 years

Int. Cl. D25—01

U.S. Cl. D18—2 B

FIG. 1 is a plan view of a molded panel showing my new design; and

FIG. 2 is a cross-sectional view taken along the line 1—2 in FIG. 1 to show the profile of the molded design.

I claim:

The ornamental design for a molded panel or similar article, substantially as shown.
